UNITED STATES PATENT OFFICE

2,476,732

ULTRA HIGH FREQUENCY COUPLING
SYSTEMGuilford L. Hollingsworth and Nick A. Schuster,
Schenectady, N. Y., assignors to General Electric Company, a corporation of New York

Application August 12, 1943, Serial No. 498,332

11 Claims. (Cl. 178—44)

1

Our invention relates to apparatus for coupling ultra-high frequency systems, and more particularly, to apparatus for coupling dielectric wave guides of the hollow-pipe type with concentric or coaxial transmission lines.

It is an object of our invention to provide a new and improved coupling device for ultra-high frequency systems.

It is another object of our invention to provide a new and improved device for coupling a dielectric wave guide of the hollow-pipe type to a coaxial or concentric transmission line.

For efficient transmission of energy from an ultra-high frequency electromagnetic wave generator to utilization devices in an ultra-high frequency signalling system, it is known that wave guides of the hollow-pipe type are preferred to concentric or coaxial cables as a transmission means where the electromagnetic waves are transmitted over an appreciable distance because of the considerably smaller losses in such wave guides. However, the physical structure of the usual type of ultra-high frequency electromagnetic wave generator usually is of such form that energy is transmitted therefrom most easily by means of a concentric or coaxial cable. Especially where large amounts of such energy are being transmitted, it is desirable that the concentric or coaxial connection to the generator be as short as possible and that the energy be transferred efficiently to a wave guide system without the introduction of reflections due to abrupt admittance discontinuities in the transmission system.

Also in the construction of ultra-high frequency signalling systems which employ rotating apparatus, for example, a rotating antenna structure, it is known that, for simplicity of mechanical structure, a concentric or coaxial cable is to be preferred for transmitting the ultra-high frequency energy through a rotating joint, while for efficiency of transmission a wave guide of the hollow-pipe type is preferable for the transmission of energy through the remainder of the system. Accordingly, it is a further object of our invention to provide a new and improved rotating coupling unit for an ultra-high frequency system.

It is a still further object of our invention to provide a new and improved device for coupling a dielectric wave guide of the hollow-pipe type to a coaxial or concentric transmission line which is particularly adapted for transmitting large amounts of ultra-high frequency energy.

Still another object of our invention is to pro-

2

vide a new and improved device for coupling a dielectric wave guide of the hollow-pipe type to a coaxial or concentric transmission line, which has a wide band-pass characteristic, and which requires no tuning adjustments.

Briefly stated, in accordance with our invention ultra-high frequency energy is transformed smoothly and efficiently from an electromagnetic wave of the TEM or transverse electromagnetic type being propagated along a coaxial or concentric transmission line to a wave of the TE or transverse electric type for propagation along a wave guide of the hollow-pipe type by means of a coupling unit in the form of an extension of the inner conductor of the transmission line projecting to the opposite wall of the wave guide and having a contour selected to match the admittances of the wave guide and the transmission line.

For a better understanding of our invention, reference may be had to the following description taken in connection with the accompanying drawings and its scope will be pointed out in the appended claims. Fig. 1 illustrates a plan view of an embodiment of our invention as applied to a system for coupling a dielectric wave guide of the hollow-pipe type and a concentric transmission line; Fig. 2 is a front elevation view, partly in section, of the system of Fig. 1 showing the position of the coupling device therein; and Fig. 3 is a side elevation view, partly in section, of the system. Figs. 4 and 5 are curves showing certain characteristics of the system of Figs. 1-3; Fig. 6 is a plan view of a modification of the system shown in Fig. 1; and Fig. 7 is a side elevation view, partly in section, of the system of Fig. 6. Fig. 8 shows the manner in which our invention may be applied to a system utilizing a rotating coupling between a pair of parallel wave guides; and Fig. 9 is an enlarged cross sectional view of a portion of the arrangement of Fig. 8.

Referring now more particularly to Figs. 1-3 jointly, we have there illustrated our invention as applied to an ultra-high frequency system peculiarly adapted for transmitting microwaves and which may comprise a dielectric wave guide 10 of the hollow-pipe type defined by conductive or metallic wall members defining therein a region through which electromagnetic waves are propagated dielectrically and to which ultra-high frequency energy is supplied from a coaxial transmission line 11, the transverse electromagnetic waves of the transmission line 11 being converted to transverse electric waves in the wave guide 10 by means of a coupling member 12.

While it is to be appreciated that the principles of our invention are applicable to systems for controlling the propagation of electromagnetic waves of other types, we have chosen to represent our invention as applied to a system where TE₀₁ electromagnetic waves may be utilized.

The dielectric wave guide 10 is shown to be of the rectangular hollow-pipe type defined by a top wall 13, a bottom wall 14, and side walls 15, these walls preferably being formed of a suitable conducting material, such as copper or brass. The wave guide 10, at its right-hand end, is closed by an end wall 16.

The concentric or coaxial transmission line 11 comprises a tubular outer conductor 17, preferably metallic in nature, and an inner conductor 18. The inner conductor 18 is electrically and mechanically connected, as by soldering or welding, to the coupling member 12 which serves to maintain the inner conductor 18 coaxially aligned with respect to the outer conductor 17 in a manner to be pointed out later. The outer conductor 17 is joined to the bottom wall 14 of the wave guide by means of a collar member 19 soldered or brazed to both the outer conductor and the bottom wall of the wave guide. The inner conductor 18 has a portion 20 of reduced diameter at its lower end which projects into a hole 21 in the end of the anode structure 22 of any suitable high frequency electron discharge device 23, such as a magnetron. The anode structure 22 is supported by means of a glass seal 24 from a thin metal tube 25 brazed to the upper portion of a metallic tank or external wall structure of the electron discharge device 23. The inner diameter of tube 25 is made equal to the inner diameter of tubular conductor 17 so that the tube 25 functions as the outer conductor of a short section of coaxial transmission line connected to the device 23, the anode structure 22 forming the inner conductor of this short section of transmission line.

Disposed between the adjacent ends of conductors 17 and 25 is a half-wave choke or connecting member 26 having a shoulder 26' at its upper end soldered or brazed to the lower end of conductor 17 and a pair of sleeves 27, 27' in concentric, spaced relation with conductor 25. A tubular sleeve 28, integral with the metallic tank of device 23, slips over the outer surface of member 26. The outer conductor 17 and member 26 are securely clamped to the tank of device 23 by means of a nut 28' engaging a thread on the outer surface of sleeve 28 and bearing against the upper surface of member 26.

The length of conductor 25 and each of the sleeves 27, 27' is made substantially equal to a quarter wave length of the high frequency wave supplied by device 23 so that these members function as a folded half-wave choke conductively connecting sections of the outer conductor of the transmission line, the points of high current density coinciding with the good electrical connections between conductor 25 and the metallic tank of device 23 and between the bottom of sleeve 27' and the aforesaid tank. In this folded half-wave choke the point of zero current occurs at the mechanical break or gap between members 25 and 26. The construction outline provides a rigidly supported inner conductor 18 which is capacitively coupled to the anode structure 22 by means of the portion 20 extending into the opening 21. Hence, strains on the anode seal of the high frequency discharge tube employed are avoided.

The coupling member 12 comprises a metallic element extending from the upper end of the inner conductor 18 of coaxial line 11 to the opposite or upper wall 13 of the wave guide system. The member 12 is substantially circular in transverse cross section, the area of the cross section of the member increasing continuously and gradually from its point of connection with the inner conductor 18, where its size is the same as that of conductor 18, to its point of connection with the wall 13. The outer contour of the member 12 is in the form of a reverse curve and is constructed by spinning a shell of any suitable conducting material, such as copper or brass. The upper portion of the coupling member 12 is concave inwardly, while the lower portion, or the portion attached to the conductor 18, is concave outwardly, these two portions being separated by a point of inflection 29, i. e., a point where the slope of the reverse curve changes from a gradually decreasing value to a gradually increasing value.

In transmitting large amounts of energy from an ultra-high frequency generator to utilization devices, it has been found that extraction of energy from the high frequency devices is most easily obtained by means of a coupling loop attached to the end of a coaxial line. On the other hand, it has been found that transmission losses of the system are reduced when the high frequency energy is transmitted through a wave guide. The coaxial line of the wave guide coupling, shown in Figs. 1-3 and described above, provides a means whereby high power may be efficiently transmitted without corona or arcing at the point of conversion from the TEM or transverse electromagnetic waves propagated along the transmission line to the TE or transverse electric waves propagated along the wave guide system. In matching the impedance of the coaxial line to that of the wave guide system, it has been found that the diameter of the coupling unit 12 is a parameter which is useful for both matching the susceptance of the wave guide and the coaxial cable, as well as the conductance of these two members.

High frequency energy flows from the coaxial line 11 to the wave guide 10 in three directions. Thus, it flows forwardly, i. e., to the left in Figs. 1 and 2, into the wave guide 10 whose admittance is matched with the admittance of any utilization devices attached therewith. The flow of energy in this direction results in a constant conductance for the coupling unit 12 whose value is substantially independent of the position of the back wall 16. Energy also flows sideways from the coupling unit 12 to the side walls 15 of the wave guide. This flow of energy results in a constant susceptance for the coupling unit whose value likewise is substantially independent of the position of the back wall. The energy may likewise flow in a third or final direction, namely, backwardly into the cavity between the unit and the back wall 16. This energy excites this cavity to produce an apparent susceptance for the coupling unit which varies with the distance between the unit and the back wall according to the relation $B = -j \cot \beta l$, where B is the value of susceptance, β is a propagation constant having the value

$$B = \frac{2\pi}{\lambda_s}$$

λ_s being the length of a wave in the guide, and l is the distance between the coupling unit 12 and

the back wall. This energy also produces an apparent conductance which also depends upon this same distance l . When this distance l is approximately equal to a quarter of a wave length of the wave propagated along the guide 10, the susceptance due to this portion of the energy division is equal to zero. Also, since some of the energy of this excited cavity is coupled into the matched wave guide 10, the conductance of the guide is increased. The magnitude of this increase is dependent upon the excitation of the cavity and increases as the back wall distance deviates from multiples of a quarter wave length of the high frequency wave.

In the curves shown in Fig. 4, the conductance and susceptance of the coupling unit are plotted against the distance of the back wall 16 from the center of the coupling unit. The curves of this figure show that the admittance of the coupling unit may be adjusted to a desired value simply by changing the spacing of a back wall with respect to the coupling unit, and that a point 30 may be found where, for a given wave length λ_g , the susceptance has a value of zero and the conductance of the unit matches the conductance of the wave guide.

By means of the curves shown in Fig. 5, there is illustrated the manner in which the conductance and susceptance of the coupling unit having a back wall position corresponding to the position 30 and determined in accordance with the manner outlined in the discussion of Fig. 4 vary with the wave length of the energy transmitted along the coaxial line 11 for propagation through the guide 10. Curve 31 shows that the conductance increases as the wave length of the transmitted wave is increased, while curve 32 shows that the susceptance of the unit changes from a positive to a negative value as the wave length is increased from a value lower than λ_g to a wave length greater than this value. Curve 33 illustrates the standing wave ratio of voltage over a range of wave lengths deviating from the desired operating wave length λ_g . From this curve it is evident that the wave length may be varied over a range of ± 5 per cent of the desired operating wave length λ_g without permitting the standing wave ratio to reach a value greater than 1.4.

Referring again to Figs. 1-3, it may be seen that the coupling unit 12 is provided with a flanged portion 35 at its upper end and an axially aligned hole 36. The flange 35 preferably is soldered to an upper wall 13 to insure good electrical contact between the coupling unit 12 and the wave guide and, also, functions to support rigidly the inner conductor 18 in a central position within outer conductor 17. The axially aligned hole 36 which extends likewise through inner conductor 18 and its extension 20 provides means whereby air, or any other cooling agent may be blown into the anode structure 22 to assist in cooling this portion of the high frequency electron discharge device utilized.

In the coaxially aligned wave guide coupling arrangement shown in Figs. 6 and 7, jointly, the wave guide 10 is provided with a curved back wall member 37 which functions to reduce the variation, with frequency, of the susceptance due to energy reflected backwardly from the coupling unit 12. By making the diameter of the upper end of the coupling unit 12 sufficiently large that it is approximately tangent to the curved back wall 37, the standing wave ratio, i. e., the ratio of the voltage at a loop of the standing wave in the

guide to the voltage at a node of the wave, in the guide 10 may be reduced and the band pass of the system increased. To further decrease the standing wave ratio in the wave guide 10, and to increase the band-pass of the coupling unit, metallic tuning diaphragms 38 are inserted in the guide 10 a calculated distance from the coupling unit 12, extending between the upper wall 13 and lower wall 14 and projecting into the wave guide 10 a distance sufficient to produce the susceptance necessary to reduce the standing wave ratio to a desired value, and to give the desired band pass.

In the arrangement shown in Fig. 8, high frequency electromagnetic waves in a wave guide 40 are transmitted to a wave guide 41 through a rotating section of concentric transmission line. The wave guide 40 may supply high frequency energy, for example, to a rotatable antenna of a high frequency signalling system used for recognition purposes and the wave guide 41 may be connected to a transmitter or a receiver. The waves being transmitted through the wave guides preferably are of the order of 10 centimeters. In such a high frequency signalling system, since lower frequency waves are also sometimes employed for additional functions of the system, the construction shown permits the use of a coaxial cable 42, also provided with a rotating section to transmit the lower frequency waves from the stationary part of the apparatus to the rotating portions thereof.

The wave guide 41 may be stationary and the wave guide 40 may be supported from a member 43 of the rotatable antenna structure, the member 43 being rigidly secured to a vertical shaft member 44 supported by means of a plurality of bearings 45, 46, 47 from a stationary support 48. The shaft 44 may have affixed thereto a gear 49 to function as means for rotating the shaft and the antenna structure.

Concentrically positioned within the shaft 44 is a coaxial or concentric cable comprising a tubular outer conductor 50 and a tubular inner conductor 51. The tubular outer conductor 50 is affixed, at its upper end, to a collar member 52 soldered or brazed to a circular opening in the bottom wall of the rectangular wave guide 40. A mating collar member 52' is attached to outer conductor 50. A pair of semicircular grooved members 53, clamped together by means of screws 54, serve to prevent separation of collar members 52, 52'. The coupling member 12, of a type similar to the coupling member described in connection with the coupling arrangement shown in Fig. 1, is connected between the inner conductor 51 at its upper extremity and the upper wall of wave guide 40.

The connection between the wave guide 41 and the inner conductor 51 is achieved by means of a similar coupling member 12'. Likewise, a circular collar member 55 attached to the opening in the upper wall of wave guide 41 functions as a lower section of the outer conductor of the coaxial cable.

In order to provide means whereby the outer conductor 50 may be rotated with respect to the collar member 55, a capacitive coupling joint is interposed between these two sections of the outer conductor. Thus, the collar member 55 is provided at its upper end with a portion 56 of enlarged inner diameter which encircles, in spaced relation, the lower end of tubular outer conductor 50. A metallic sleeve 57 having a length equal to a quarter wave length at the frequency of the

the wave transmitted through the coaxial cable 50, 51 is attached to the outer conductor 50 at a point spaced one quarter wave length from the lower end of the conductor 50. The length of the portion 56 is likewise made equal to a quarter wave length at the operating frequency and the inner diameter of the lower portion of the sleeve 57 is made equal to the inner diameter of the portion 56. Thus, from the construction as shown in Fig. 8, it is evident that there is a mechanical break between the conductor 50 and the conductor 55 and between the sleeve 57 and the sleeve 56. These two mechanical breaks are spaced apart by a distance equal to a quarter wave length at the operating frequency. In this way, the sleeve 57 is connected by soldering or brazing to tubular conductor 50 at a point of high current density to provide conduction of such current. The gap between the ends of members 56 and 57 occurs at a point of zero current on the line so that energy conduction in the tubular outer conductor of the coaxial line described is provided without the introduction of any objectionable reflections, as well as without the creation of any corona or electric discharge.

A tubular supporting member 59 is slipped over the collar 55 and provides means for supporting the stationary half of the race of the ball bearing 47. The rotating portion of the race is attached to tubular sleeve 60 mechanically connected to the shaft 44 at its lower end. The sleeve 60 is secured to the sleeve 57 attached to tubular outer conductor 50 as previously described. A needle bearing 61 is likewise provided between the members 59 and 60 to facilitate rotation therebetween and to assure proper alignment and spacing of the previously described electric connection between tubular conductor 50 and tubular collar 55.

In Fig. 9, we have shown in detail the construction of the rotating joint in the inner conductor 51, as well as the manner in which the concentric or coaxial cable 42 is arranged within the conductor 51 for conveying signals of lower frequency. Both coupling members 12, 12' are provided with axial holes through which the coaxial cable 42 is passed. The lower end of coupling unit 12 is joined to a sleeve member 64 having a portion 65 of reduced outer diameter, the length of the portion 65 being made equal to a quarter wave length at the frequency of the wave transmitted over the coaxial cable 50, 51. A similar sleeve member 66 is secured to the upper end of the lower portion of tubular inner conductor 51. The sleeve member 66 is likewise provided with a portion 67 of reduced outer diameter, the length of the portion 67 being made substantially equal to a quarter wave length at the operating frequency of the line. A tubular conductor 68 attached at its lower end to member 66 and having a length substantially equal to a half wave length at the operating frequency of the line is in spaced relation with both the portions 65 and 67. By means of this construction, good electrical conductivity is provided between conductor 68 and sleeve 66 and between sleeve 64 and the coupling unit 12 at points of high current density. On the other hand, the mechanical break between the portions 65 and 67 occurs at a point of zero current density and it is apparent, therefore, that continuous conduction of the high frequency currents through the tubular inner conductor of the coaxial line is provided without the introduction of any objectionable discontinuities to create standing waves on the transmission line.

The coaxial line 42 within the tubular inner conductor 51 is enclosed within a metallic pipe 70 of steel or any suitable material which functions not only to align and support the coaxial cable 42 within the tubular inner conductor 51, but also conductively to connect the flexible metallic outer conductor 71 of cable 42 at its upper end with a connecting plug 72 and at its lower end with contact fingers 73. The connecting plug 72 is tubular in form and encloses a contact body 74 slotted in its opposite ends for engaging, at its lower end, the inner conductor 75 of line 42 and, at its upper end, the inner conductor 76 of a concentric line connected to communication or control circuits in the antenna structure.

At its lower end where the cable 42 passes through coupling member 12', the inner conductor of the coaxial cable 42 is provided with a contact member 78 which engages the split fingers 79 at the upper end of a contact plug 80. Both the contact fingers 73 and the contact body 80 are supported by means of a pin 82 of insulating material within an end ring 83 attached by means of screws 83' to the bottom end of coupling member 12'. A tubular support 84 retained within the central hole of coupling unit 12' serves as means for supporting a bearing member 85 which rotatably engages a flanged bushing 86, secured, as by brazing, to the metal pipe 70.

In the operation of the rotating high frequency joints shown in Figs. 8 and 9, as the shaft 44 and the associated structure which it supports are rotated by any suitable driving means mechanically connected to gear 49, conduction of high frequency energy over the coaxial line comprising conductors 50, 51 is maintained through the capacitive joints of the inner and outer conductors thereof. The needle bearing arrangement shown at the lower end of Fig. 8 assures alignment of the sections of the tubular outer conductor 50. The pipe 70, provided with a plurality of bearings 85' positioned between itself and the tubular inner conductor 51, functions to maintain the inner conductor 51 coaxially aligned with the outer conductor 50. Continuous conduction between the rotatable sections of the inner and outer conductors of coaxial line 52 is secured through the contact finger arrangement shown in detail in the bottom of Fig. 9. Thus, it is seen that the tubular inner conductor 51 is stationary with respect to wave guide 41 throughout its length up to the mechanical break between conductor 68 and sleeve 64. On the other hand, the tubular outer conductor 50 and the concentric cable 42 with its supporting pipe 70 are rotatable throughout the major portion of their length with respect to the wave guide 41. Both coaxial lines are supported entirely by means of the conversion or coupling units 12, 12', thus avoiding the mechanical inconvenience of using auxiliary supporting devices. Such a structure permits the use of relatively small bearings for supporting the rotating antenna in a high frequency signalling system, as well as provides means for using a minimum length of coaxial lines to connect relatively rotatable sections of a wave guide system carrying large amounts of high frequency power.

It is thus seen that our conversion unit for coupling a concentric transmission line to a wave guide permits the transmission of large amounts of high frequency power without the arising of any objectionable corona or electric discharges, 75 or objectionable reflections and standing waves.

Because of the simple construction of the unit, it is easily attached to high frequency electric discharge devices, and is also especially well adapted for transmitting large amounts of high frequency power between rotating units of a high frequency signalling system.

While we have shown particular embodiments of our invention, it will of course be understood that we do not wish to be limited thereto since various modifications may be made, and we contemplate by the appended claims to cover any such modifications as fall within the true spirit and scope of our invention.

What we claim as new and desire to secure by Letters Patent of the United States is:

1. In a system for transmitting ultra-high frequency electromagnetic waves from a concentric transmission line to a dielectric wave guide of the hollow-pipe type, means for converting transverse electromagnetic waves being propagated along said transmission line to transverse electric waves for propagation through said guide, said means comprising a metallic member extending across said guide and electrically connected between the inner conductor of said transmission line and a wall of said guide, said member being substantially circular in transverse cross section and having a transverse diameter increasing continuously between the points of connection of said conductor and said wall to provide a contour of the form of a reversed curve and of such dimensions that the susceptance and conductance of said guide and said line are matched over a broad band of frequencies whereby waves of frequencies in said band may be transmitted between said guide and said line substantially without reflection.

2. In a system for transmitting ultra-high frequency electromagnetic waves from a concentric transmission line to a dielectric wave guide of the hollow-pipe type, means for converting transverse electromagnetic waves being propagated along said transmission line to transverse electric waves for propagation through said guide, said means comprising a metallic member extending across said guide and electrically connected between the inner conductor of said transmission line and a wall of said guide, said member being substantially circular in transverse cross section, the cross-sectional diameter of said member increasing continuously between the points of connection of said conductor and said wall, the average diameter of the cross section of said member being greater than that of said inner conductor and sufficiently large and of such shape as to match the susceptance and conductance of said transmission line whereby waves varying in frequency over a broad band of frequencies may be transmitted between said guide and said line substantially without reflection.

3. In combination, a dielectric wave guide of the hollow-pipe type, a concentric transmission line comprising a tubular outer conductor and an inner conductor, said outer conductor being electrically connected to said wave guide, and means for coupling said guide and said transmission line comprising a metallic member extending across said wave guide transverse to the direction of propagation of waves therein and electrically connected between said inner conductor at its end adjacent said guide and the opposite inner wall of said guide, said member being substantially circular in transverse cross section, the area of the cross section of said member increasing continuously and gradually be-

tween its point of connection with said inner conductor and its point of connection with said wall.

4. In combination, a hollow wave guide, a concentric transmission line projecting from one side thereof and coupled thereto, the outer conductor of said line being conductively connected to the adjacent wall of said guide and the inner conductor of said line projecting through said wall and being connected conductively to the opposite wall of said guide, the portion of said inner conductor projecting across said guide having a continuously and rapidly increasing diameter between said walls of said guide.

5. In a microwave signalling system, the combination of a rectangular wave guide of the hollow-pipe type, a coaxial transmission line connected therewith, and means for converting the high frequency electromagnetic waves transmitted between said wave guide and said line, said means comprising a coupling member extending across said guide and electrically connected between the inner conductor of said line and the opposite wall of said guide, said member having a substantially circular transverse cross section continuously increasing in magnitude from the size of said inner conductor at its point of connection therewith to a size at its point of connection with said wall sufficiently large to match substantially completely the susceptance and conductance of said wave guide.

6. In a system for transmitting ultra-high frequency electromagnetic waves from a concentric transmission line to a dielectric wave guide of the hollow-pipe type, means for converting transverse electromagnetic waves being propagated along said transmission line to transverse electric waves for propagation through said guide, said means comprising a metallic member extending across said guide and electrically connected between the inner conductor of said transmission line and a wall of said guide, said member being substantially circular in transverse cross section and having a contour of the form of a reversed curve and including a point of inflection, the diameter of the cross section of said member between said point and said wall being sufficiently large to match the susceptances of said transmission line and said wave guide and the diameter of the cross section of said member between said point and said inner conductor being sufficiently small to match the conductances of said wave guide and said transmission line.

7. In an ultra-high frequency transmission system, the combination of, a stationary wave guide, a rotating wave guide, a coaxial transmission line having an inner conductor and a tubular outer conductor connected between said wave guides, said transmission line having a pair of rotatably supported sections, and high frequency energy coupling means connected between said inner conductor at its opposite ends and the walls of an associated one of said wave guides, said means comprising a metallic member substantially circular in transverse cross section, the area of the cross section thereof increasing gradually and continuously from the area of said inner conductor at its point of connection therewith to a value at its point of connection with the said wall of said wave guide sufficiently large to match substantially completely the susceptance and conductance of said wave guide.

8. In a system for translating ultra-high frequency electromagnetic waves and lower frequency waves between two relatively movable por-

11

tions thereof, the combination of a pair of wave guides of the hollow-pipe type for transmitting ultra-high frequency waves, a first transmission line having a tubular inner conductor and a concentric outer conductor connected between said wave guides, said transmission line comprising a pair of adjacent sections supported for rotation with respect to each other whereby said wave guides may be rotated with respect to each other, coupling means connected between said inner conductor at its opposite ends and a wall of the wave guide associated therewith for converting the transverse electromagnetic waves propagated along said transmission line to transverse electric waves for propagation along said wave guides, each of said coupling means having a hole therethrough concentrically aligned with said inner conductor, and a second concentric transmission line for transmitting lower frequency waves passing through said holes and said inner conductor, said second transmission line comprising a pair of adjacent sections supported for rotation with respect to each other, each of said sections of said second transmission line being mechanically connected to a corresponding section of said first transmission line.

9. In an ultra-high frequency signalling system, an electron discharge device having an output electrode, a dielectric wave guide of the hollow-pipe type, and means for transmitting energy from said electrode to said wave guide, said means comprising a section of concentric transmission line having an inner conductor, said conductor having one of its ends in spaced relation with and coupled to said electrode, and means for converting transverse electromagnetic waves being propagated along said line to transverse electric waves for propagation through said guide, said last means comprising a metallic member extending across said guide and rigidly connected between said conductor at its other end and a wall of said guide to support said conductor in said spaced relation with said electrode, said member increasing continuously in transverse section between said conductor and said wall of said guide and having an average diameter greater than that of said inner conductor.

10. In an ultra-high frequency signalling system, an electron discharge device having an output electrode, a dielectric wave guide of the hollow-pipe type, a concentric transmission line connected between said device and said wave guide, said transmission line comprising a tubular outer conductor and a tubular inner conductor having one of its ends in spaced relation with said electrode and capacitively coupled thereto, and means for supporting said inner conductor in said spaced relation and for converting transverse electromagnetic waves being propagated

12

along said transmission line to transverse electric waves for propagation through said wave guide, said means comprising a metallic member rigidly connected between said inner conductor at its other end and an inner wall of said wave guide, said member having a passage therethrough connected with said inner conductor for conveying cooling medium through said passage and said inner conductor to said electrode.

10. 11. In an ultra-high frequency signalling system, an electron discharge device having an output electrode, a dielectric wave guide of the hollow-pipe type, a concentric transmission line connected between said device and said wave guide, said transmission line comprising a tubular outer conductor and a tubular inner conductor having one of its ends in spaced relation with said electrode and capacitively coupled thereto, and means for supporting said inner conductor in said spaced relation and for converting transverse electromagnetic waves being propagated along said transmission line to transverse electric waves for propagation through said wave guide, said means comprising a metallic member rigidly connected between said inner conductor at its other end and an inner wall of said wave guide, said member having a substantially circular transverse cross section of continuously increasing diameter between its point of connection with said inner conductor and said inner wall and of sufficient size to match the susceptance and conductance of said wave guide, and an axial hole through said member connecting with said tubular inner conductor for conveying cooling medium through said inner conductor to said electrode.
